Design for Cooking Stoves

J. Martin

J. Stuart & R. Peterson

Patented Sept 10, 1852

Des. 1147

John Martine, of Philadelphia, Pa.

Assignor, to

D. Stuart & J. A. Peterson, of same place.

Letters Patent No. 1147. Dated Sept. 26. 1857.

The schedule referred to in these Letters Patent and making part of the same.

To all, whom it may concern:

Be it known that I, John Martine, of the City and County of Philadelphia, and State of Pennsylvania, have invented or produced a new and original design for the plates of a Cooking Stove, and I do hereby declare the following to be a full, clear and exact description of the same, reference being had to the accompanying drawing, and to the letters of reference marked thereon.

My design relates to the shape, configuration, and ornamental mouldings, of the front side & top plates of a cooking stove, which I term the Young America.

On reference to the accompanying drawing, which forms a part of this specification,

Fig. 1. represents the front plate,

2

Des. 11/47

Fig. 2. the side plate. Fig. 3. the top plate, and
Fig. 4. a section of the moulding on the edge of the top plate of the Young America
Cooking Stove.

On the upper edge of the front plate Fig. 1. is a plain heading a, and below the latter a denticulated heading b, between which is the curved moulding c, having openings d, interspersed with a zigzag rib and sprigs.

On the bottom of the plate is a moulding e, composed of plain beads and fillets, and on the sides of the plate are a series of vertical flutes with diamond shaped ornaments.

The front plate is furnished with the usual doors A and A', each of which is edged with a plain moulding inclosing a denticulated moulding within which is a panel to be left plain as illustrated or furnished with any desired foliated ornaments.

The side plate Fig. 2. is edged on the top and bottom and the opposite ends with a moulding consisting of plain beads and fillets and has an oven door B, a smaller door C, and a panel D, the whole of which are edged with a plain moulding similar in character to that of the doors A and A' of the front plate, the enclosed spaces being either left plain or furnished with any desired ornament.

The form of the top plate is fully represented in Fig. 3. the moulding on its edge being illustrated in section and drawn to the full size in Fig. 4.

I claim the combination and arrangement of ornamental figures & forms represented in and by the accompanying drawing as forming together an ornamental design for the front, side, and top plates of a cooking stove.

In testimony whereof I have signed my name to this specification in the presence of two subscribing witnesses.

Witnesses.

Henry Cowson.
A. H. Perkins

John Martino.
